PICKER STICK CHECK

Felix Houston Pressley, Pelzer, S. C., assignor of
one-half to William D. Dodenhoff, Green-
ville, S. C.

Application May 31, 1940, Serial No. 338,180

10 Claims. (Cl. 139—165)

This invention relates to a novel picker stick check for looms and more especially to a device of this character in which a friction clutch is employed.

5 Looms are generally constructed so that the picker stick will be given a very short and rapid acceleration when the shuttle is projected across the loom. This is commonly called the inward stroke of the stick. The outward or return stroke 10 usually is partially produced by a spring which acts upon the lower end of the picker stick which returns the stick nearly to its original position. The remaining movement is imparted by the incoming shuttle. It is very essential to gradually arrest the picker stick so that the shuttle 15 will not rebound in the shuttle box and cause a mispick on the next stroke of the stick.

It is an object of this invention to provide a 20 picker stick check comprising a friction clutch which will resist the outward travel of the picker stick a greater amount than the inward travel. Due to the necessity of accurately stopping the picker at the proper point after the shuttle engages the same, a clutch of the above-mentioned 25 type has been provided. When the stick travels inwardly to propel the shuttle out of the box, however, the location and the point of stoppage of the picker is not so important; consequently, a lesser resisting force is employed.

30 It is another object of this invention to provide a picker stick check having means for initially and gradually resisting the momentum of the picker stick, in combination with a secondary resisting means for limiting the movement of the first-named means. In other words, a clutch is employed for gradually resisting the momentum of the picker stick and stationary adjustable stops are employed for limiting distances that the clutch can be moved.

40 It is another object of this invention to provide a check of the class described which is rigidly supported by the rocker stand and the lay sword thereby lessening the load heretofore ordinarily carried by the lay and positioning the parts closer 45 to the rocker shaft. As a result, the momentum of the lay is reduced accordingly.

Some of the objects of the invention having been stated, other objects will appear as the description proceeds when taken in connection with the accompanying drawings, in which—

50 Figure 1 is an elevation of a portion of a loom, showing portions of the frame in section, with my improved checking device associated therewith;

Figure 2 is an elevation looking along the line 2—2 in Figure 1;

Figure 3 is a sectional plan view taken along the line 3—3 in Figure 1;

Figure 4 is a sectional plan view taken along 5 the line 4—4 in Figure 1;

Figure 5 is a sectional plan view taken along the line 5—5 in Figure 1;

Figure 6 is a sectional plan view taken along 10 the line 6—6 in Figure 1;

Figure 7 is a vertical sectional view taken along the line 7—7 in Figure 1.

Referring more specifically to the drawings, the numeral 10 denotes a portion of a loom frame in which is rotatably mounted the rocker shaft 15 11, said rocker shaft having a sword 12 mounted thereon, and this sword extends upwardly for supporting a lay 14. The lay 14 extends across the loom and the intermediate portion thereof has a reed 15 therein through which warp ends, 20 not shown, are adapted to pass during a weaving operation. The top of the lay 14 serves as a raceway for a shuttle 16 which travels back and forth through the sheds of the warp.

Disposed on the extreme end of the lay 14 is 25 a shuttle box 17 which is adapted to receive the shuttle 17 when it is propelled from the opposite end of the lay. While disposed in this shuttle box, a suitable picker 18 serves as an impact receiving member for checking the momentum of 30 the shuttle as well as an impact delivering member for propelling the shuttle out of the box.

Picker 18 is secured upon the upper end of a picker stick 19, the lower end of said picker stick having a rocker shoe 20 thereon which rests upon 35 a rocker shoe support 21 on the end of rocker shaft 11. During the operation of the loom, the upper end of the picker stick 19 is adapted to rock back and forth from bold line position to dotted line position as shown in Figure 1, so as 40 to expel the shuttle 16 from the shuttle box at the proper time. The lay is provided with a suitable slot 26 in which the upper end of the picker stick will operate.

The means for delivering the necessary impact 45 to the picker stick 19 to cause it to expel the shuttle from the shuttle box comprises a suitable lug strap 27 and this lug strap is pulled to the left in Figure 1 at the proper time by a suitable pick motion not shown. When the picker stick 50 has moved its maximum stroke to dotted line position in Figure 1 to expel the shuttle, it is partially returned to bold line position by means of a suitable torsion spring 29, which torsion spring serves to rotate a drum 30 in a clockwise 55

manner at all times, said drum being mounted on a bolt 35.

Connected to the drum 30 as at 31 is a flexible strap 32, said strap also being secured to the lower end of the picker stick 19 as at 33. As the drum 30 moves in a clockwise manner due to the torsional force exerted by the spring 29, the picker stick will be caused to rotate in a clockwise manner to be partially returned to bold line position (Figure 1). The final return movement of the picker stick and the picker is produced by the incoming shuttle which engages the picker at a high speed. The picker gradually gives way under the impact and returns to the bold line position in Figure 1. The parts thus described are conventional, but it is thought to be necessary to disclose this much of the old structure in order to more clearly illustrate the utility of the present invention.

Secured to the picker stick shoe support as at 35 is a vertically disposed bar 36, which bar has connected thereto as at 37 a horizontally disposed bar 38. The bar 38 has its other end secured to the intermediate portion of lay sword 12 by means of a cap plate 39, and bolts 40, said members 36 and 38 constituting a framework which supports the picker stick checking device, hereinafter to be described. As the lay sword 12 and the rocker shaft 11 move back and forth during a weaving operation, this framework also rocks back and forth together with the associated picker stick check.

The intermediate portion of the vertically disposed bar 36 has a stud shaft 42 extending therefrom, upon which is rotatably mounted a cylindrical member or drum 43. The periphery of this drum is encircled by arcuate brake shoes 44 and 45, said brake shoes being pivoted together as at 46, and the shoe 45 being anchored to bar 36 as at 45a. Brake shoes 44 and 45 also have brake linings 47 and 48 respectively secured to the interior of the peripheries thereof, which brake linings are adapted to contact the periphery of the cylindrical member 43 and offer the desired resistance.

It will be noted that the arcuate member 44 and its associated brake lining 47 is considerably shorter than the arcuate member 45 and its associated brake lining 48. This condition creates a very much greater resistance to the clockwise rotation of the cylindrical member 43 than is offered when said cylindrical member is rotated in a counter-clockwise manner in Figure 1. The free end of the arcuate member 44 has a boss 49 integral therewith in which a vertically disposed bore is provided for the reception of a vertically disposed bolt 50. The lower end of the bolt 50 is adapted to slidably penetrate the free end of arcuate member 45 and the projecting end of the bolt has a compression spring 51 mounted therearound. This compression spring is confined upon the lower end of the bolt and beneath the free end of arcuate member 45 by means of a nut 52. The upper end of the bolt 50 passes beyond the boss 49 and has pivoted thereto as at 54, a suitable cam member 55. When it is desired to release the pressure of the friction members 47 and 48 upon the periphery of the drum 43, it is only necessary to rotate a cam member 55 in a counter-clockwise manner in Figure 1, thereby inverting the same and allowing the bolt to move downwardly a sufficient amount to allow the free end of the arcuate members 44 and 45 to be spread apart from each other. In normal operation of the

loom, however, the parts are in the position shown in Figure 1. The drum 43 has flanges to assist in confining parts 44 and 45 thereon.

It is to be understood that several positions may be occupied by cam member 55, depending upon the resistance desired to be offered by the clutch. For example, when the boss 49 is contacted by the nose portion 55a, the resistance is increased beyond the resistance offered when the cam is in the position shown. Any intermediate position occupied will effect a proportional amount of resistance. In other words, the shorter the distance between pivot 54 and boss 49, the smaller will be the resistance offered by the clutch.

A vertically disposed bar 60 is provided which has the lower end thereof secured to the face of flanged drum 43 by any suitable means such as stud bolts 61 (see Figures 1 and 7). This bar projects upwardly and is adapted to pass through a slot 63, said slot being formed by a suitable means such as strap iron members 64, 65, and 66, and suitable washers 67, made of any suitable material but are preferably made of leather fibre. The washers 67 are provided near the ends of the members 64, 65 and 66 to serve as stops to limit the travel of the vertically disposed bar 60 and are held between the strap iron members 64 and 65 by means of bolts or rivets 68, said bolts or rivets penetrating slots 69 which coincide with each other and which are disposed on opposed ends of each of the members 64, 65 and 66. The assembly as shown in Figure 4, is secured to the upper end of the bar 36 as at 71.

When it is desired to adjust the position of the washers 67 to thereby cut down the length of the slots 63, it is only necessary to loosen the bolts 68 and move the washers and bolts inwardly toward each other and again tighten the bolts.

The upper end of the bar 60 has a U-shaped member secured thereto, which in the present instance is made from strap iron, the ends of said strap iron member having slots 76 therein. If desired, members 75 may be made from other suitable material, such as leather, fiber or canvas without departing from the spirit of the invention. The slots are penetrated by a bolt 78. Bolt 78 also penetrates an impact receiving member 79 and as well as the upper end of the bar 60, in the manner shown in Figures 1 and 3. This U-shaped member encircles the intermediate portion of the picker stick 19.

The base of the U-shaped member 75 has an impact receiving member 81 mounted therein and this member is disposed on the opposite side of the picker stick from the impact receiving member 79. When it is desired to increase or decrease the distance between the impact receiving members 79 and 81, it is only necessary to manipulate the bolt 78 and move the U-shaped member 75 to the desired position.

During the operation of the loom, the lug strap 27 is caused to move to the left at the proper time in Figure 1, to propel the shuttle 16 out of the shuttle box 17 and through the warp shed. After the picker stick has exerted its initial stroke to the shuttle, it engages the impact receiving member 79 and thereafter its movement is resisted by the arm 60 and the clutch mechanism therebelow. In other words, when the picker stick 19 engages the impact receiving member 79, the arm is rotated in a counter-clockwise manner thereby rotating the cylindrical member 75

43 in the same direction. Due to the fact that the arcuate members 44 and 45 are secured in a stationary position relative to the bar 36 by means of the bolt 45a, the brake linings 47 and 48 will offer a resistance to the turning of the arm 60 and the drum 43. When the picker stick is finally checked, the parts will assume the dotted line position as shown in Figure 1. The picker stick 16 will then be caused to return partially to its original position by means of the torsion spring 29, previously described. Upon the next pick the shuttle will be thrown from the other side of the lay and caused to engage picker 18 on the upper end of picker stick 19 to restore the picker stick 19 to its original bold line position. However, this return will be gradual due to the fact that the picker stick will engage the impact receiving member 81 and when this member is thus engaged, it will be necessary to rotate the arm 60 and the cylindrical member 43 in a clockwise manner (Figure 1). When rotating in this direction, the friction brake bands 47 and 48 will offer resistance to the turning. In fact, as previously described, the resistance offered by the brake linings 47 and 48 will be considerably greater when the drum is rotated in a clockwise manner than will be the case when the drum is rotated in a counterclockwise manner. This is a very important feature, because it is very necessary that the shuttle 16 be properly arrested as it enters the shuttle box so that the picker will be in the proper position for expelling the shuttle upon the next pick.

The washers 67 are mounted in a stationary position so as to act as a secondary check for the clutch mechanism.

In the drawings and specification, there has been set forth a preferred embodiment of the invention, and although specific terms are employed, they are used in a generic and descriptive sense only and not for purposes of limitation, the scope of the invention being set forth in the appended claims.

I claim:

1. In a loom having a rocker shaft with a lay sword and a rocker shoe support mounted therein, a picker stick mounted on said rocker shoe support, a picker stick check comprising a framework jointly supported by said sword and shoe support, a rigid arm pivotally mounted in said framework, said arm having an abutting member positioned in the path of said picker stick to engage one side thereof, a complementary abutting member for engaging the opposite side of said picker stick, said abutting members being positioned to engage the stick in advance of the limits of the inward and outward travel, a friction clutch resisting the travel of said abutting members, and means for causing said clutch to exert its maximum resistance on the outward travel of the picker stick, a rotatably mounted cylindrical member attached to said arm, a pair of stationary pivotally connected brake shoes engaging the periphery of said cylindrical member, one of said brake shoes encircling a greater portion of the periphery of the cylindrical member than the other and having its free end pointed in an opposed direction to the direction of rotation of said cylindrical member when the picker stick moves outwardly, and spring-pressed means normally forcing the free ends of said shoes toward each other.

2. In a loom having a rocker shaft with a lay sword and a rocker shoe support mounted therein, a picker stick mounted on said rocker shoe

support, a picker stick check, comprising a framework, jointly supported by said sword and shoe support, a rigid arm pivotally mounted on said framework, said arm having an abutting member positioned in the path of said picker stick to engage one side thereof, a complementary abutting member for engaging the opposite side of said picker stick, said abutting members being positioned to engage the stick in advance of the limits of the inward and outward travel, a friction clutch resisting the travel of said abutting members, means for causing said clutch to exert its maximum resistance on the outward travel of the picker stick, and means for limiting the distance travelled by said pivoted arm during the inward and outward strokes of the picker stick, a rotatably mounted cylindrical member attached to said arm, a pair of stationary pivotally connected brake shoes engaging the periphery of said cylindrical member, one of said brake shoes encircling a greater portion of the periphery of the cylindrical member than the other and having its free end pointed in an opposed direction to the direction of rotation of said cylindrical member when the picker stick moves outwardly, and spring-pressed means normally forcing the free ends of said shoes toward each other.

3. In a loom having a rocker shaft with a lay sword and a rocker shoe support mounted thereon, a picker stick mounted on said rocker shoe support, a picker stick check comprising a framework jointly supported by said sword and shoe support, a rigid arm pivotally mounted on said framework, said arm having an abutting member positioned in the path of said picker stick to engage one side thereof, a complementary abutting member for engaging the opposite side of said picker stick, said abutting members being positioned to engage the stick in advance of the limits of its inward and outward travel, a cylindrical member rotatably mounted on said framework and attached to said pivoted arm, and a pair of pivotally connected brake shoes resiliently engaging the periphery of said cylindrical members and being non-rotatably secured to the framework whereby the inward and outward travel of said picker stick will be resisted, one of said brake shoes encircling a greater portion of the periphery of the cylindrical member than the other and having its free end pointed in an opposed direction to the direction of rotation of said cylindrical member when the picker stick moves outwardly, and spring-pressed means normally forcing the free ends of said shoes toward each other.

4. In a loom having a rocker shaft with a lay sword and a rocker shoe support mounted thereon, a picker stick mounted on said rocker shoe support, a picker stick check comprising a framework jointly supported by said sword and shoe support, a rigid arm, said arm having an abutting member positioned in the path of said picker stick to engage one side thereof, a complementary abutting member for engaging the opposite side of said picker stick, said abutting members being positioned to engage the stick in advance of the limits of its inward and outward travel, a cylindrical member rotatably mounted on said framework and attached to the lower end of said arm, and a pair of pivotally connected brake shoes, resiliently engaging the periphery of said cylindrical member and being non-rotatably secured to the framework one of said brake shoes encircling a greater portion of the periphery of

the cylindrical member than the other and having its free end pointed in an opposed direction to the direction of rotation of said cylindrical member when the picker stick moves outwardly, whereby the inward and outward travel of said picker stick will be resisted, and means for limiting the distance travelled by said pivoted arm during the inward and outward strokes of the picker stick.

10 5. In a loom having a rocker shaft with a lay sword and a rocker shoe support mounted thereon, a picker stick mounted on said rocker shoe support, a picker stick check, comprising a framework jointly supported by said sword and shoe support, a rigid arm pivotally mounted on said framework, said arm having an abutting member positioned in the path of said picker stick to engage one side thereof, a complementary abutting member for engaging the opposite side of said picker stick, said abutting members being positioned to engage the picker stick in advance of the limits of its inward and outward travel, a cylindrical member rotatably mounted on said framework and attached to said pivoted arm, a pair of pivotally connected brake shoes engaging the periphery of said cylindrical member and being non-rotatably secured to said framework, one of said brake shoes encircling a greater portion of the periphery of the cylindrical member than the other and having its free end pointed in an opposed direction to the direction of rotation of said cylindrical member when the picker stick moves outwardly, and spring-pressed means normally forcing the free ends of said shoes toward each other.

6. In a loom having a rocker shaft with a lay sword and a rocker shoe support mounted thereon, a picker stick mounted on said rocker shoe support, a picker stick check comprising a framework jointly supported by said sword and shoe support, a rigid arm pivotally mounted on said framework, said arm having an abutting member positioned in the path of said picker stick to engage one side thereof, a complementary abutting member for engaging the opposite side of said picker stick, said abutting members being positioned to engage the stick in advance of the limits of its inward and outward travel, a cylindrical member rotatably mounted on said framework and attached to said pivoted arm, a pair of pivotally connected brake shoes engaging the periphery of said cylindrical member and being non-rotatably secured to said framework, one of said brake shoes encircling a greater portion of the periphery of the cylindrical member than the other and having its free end pointed in an opposed direction to the direction of rotation of said cylindrical member when the picker stick moves outwardly, spring-pressed means normally forcing the free ends of said shoes toward each other, and an adjustable stop mounted on each side of said arm for limiting the travel thereof during the inward and outward strokes of the picker stick.

65 7. In a picker stick mechanism comprising a picker stick having a rocker shoe, a rocker shoe

stand and means for actuating said picker stick, a picker stick check comprising a pivoted arm supported by said shoe, said arm having oppositely disposed abutting surfaces disposed in the path of the picker stick during the inward and outward strokes, a rotatably mounted cylindrical member attached to said arm, a pair of stationary pivotally connected brake shoes engaging the periphery of said cylindrical member, one of said brake shoes encircling a greater portion 10 of the periphery of the cylindrical member than the other and having its free end pointed in an opposed direction to the direction of rotation of said cylindrical member when the picker stick moves outwardly, and spring-pressed means normally forcing the free ends of said shoes toward each other. 15

8. In a picker stick mechanism comprising a picker stick having a rocker shoe, a rocker shoe stand and means for actuating said picker stick, 20 a picker stick check comprising a pivoted arm supported by said shoe, said arm having oppositely disposed abutting surfaces disposed in the path of the picker stick during the inward and outward strokes, a rotatably mounted cylindrical member attached to said arm, a pair of stationary pivotally connected brake shoes engaging the periphery of said cylindrical member, one of said brake shoes encircling a greater portion of the periphery of the cylindrical member 30 than the other and having its free end pointed in an opposed direction to the direction of rotation of said cylindrical member when the picker stick moves outwardly, spring-pressed means normally forcing the free ends of said shoes toward each other, and an adjustable stop mounted on each side of said arm for limiting the travel thereof during the inward and outward strokes 35 of the picker stick.

9. In a loom having a rocker shaft with a lay 40
sword, and a rocker shoe support mounted there-
on, a picker stick mounted on said rocker shoe
support, a picker stick check comprising a frame-
work jointly supported by the sword and the
shoe support, a rigid arm pivotally mounted on 45
the framework, a friction drum for arresting the
movement of the picker stick as it is moved in
both directions in receiving and expelling a
shuttle, and additional means on the framework
adapted to be engaged by the picker stick in its 50
swinging movement for also assisting in the
stopping of the movements of the picker stick.

55 10. In a loom having a picker stick for expelling and receiving a shuttle, said loom also having a rocker shaft and a sword, a framework mounted on the rocker shaft and having its upper portion secured to said sword, friction means for retarding the travel of the picker stick during its oscillations in both directions in receiving and expelling the shuttle, and a pair of abutments carried by said framework for finally stopping the picker stick in its movement in both directions after it has been retarded by said friction means. 60
